UNITED STATES PATENT OFFICE.

LOUIS F. PERKETT, OF TRAVERSE CITY, MICHIGAN, ASSIGNOR TO TRAVERSE CITY
REFRIGERATOR CO., OF TRAVERSE CITY, MICHIGAN, A CORPORATION OF MICHIGAN.

REFRIGERATOR CONSTRUCTION.

1,312,868.

Specification of Letters Patent.

Patented Aug. 12, 1919.

Application filed November 12, 1917. Serial No. 201,421.

To all whom it may concern:

Be it known that I, LOUIS F. PERKETT, a citizen of the United States, residing at Traverse City, in the county of Grand 5 Traverse and State of Michigan, have invented certain new and useful Improvements in Refrigerator Construction, of which the following is a specification.

This invention relates to improvements in 10 refrigerator construction and one of the objects of the same is to cheapen the cost of manufacture and to provide a light and durable refrigerator having its walls constructed of fiber board, and which will at 15 the same time be moisture and heat-proof.

A further object is to provide an improved 20 refrigerator of this character which will be of a sectional construction, the walls being formed of units, thereby facilitating the assembling and manufacture of the device.

To the attainment of these ends and the accomplishment of other new and useful objects as will appear, the invention consists in the features of novelty in substantially 25 the construction, combination and arrangement of the several parts, hereinafter more fully described and claimed and shown in the accompanying drawings illustrating the invention, and in which:

30 Figure 1 is a vertical longitudinal sectional view of an improved refrigerator of this character constructed in accordance with the principles of this invention, and as taken on line 1—1, Fig. 2.

35 Fig. 2 is a vertical longitudinal sectional view taken on line 2—2, Fig. 1.

Fig. 3 is a horizontal sectional view taken on line 3—3, Fig. 1.

40 Fig. 4 is a horizontal sectional view taken on line 4—4, Fig. 1.

Fig. 5 is a detail perspective view of one of the units or sections constituting one of the walls of the refrigerator and with a portion broken away.

45 Fig. 6 is a detail perspective view of the bottom section or unit.

In the present invention, the refrigerator comprises an inner and an outer casing, the inner casing constituting the ice and food 50 compartments and is constructed of sections, each section constituting a complete unit and the units form the side, top, back and bottom walls of the compartment.

In Fig. 5, one of the upright wall units is

shown and comprises a frame work 10 having an intermediate supporting member or cleat which latter extends lengthwise of the frame, so as to run parallel with the side members of the frame.

Secured to each face of the frame thus formed, is a facing 13, of sheet material, such as fiber board, so that the space within the frame and on each side of the central member 11 will form a closed dead air space.

Secured to the section thus formed and 65 extending laterally beyond one face thereof are upright parallel members 14, which are preferably of a length to extend a short distance above the top of the section. The parts thus formed and secured together 70 constitute a complete unit, and both of the side walls are formed in this manner. The bottom member constitutes a base comprising a plurality of horizontally disposed parallel members 15 secured to the top of which is 75 a sheet of material 16, preferably of fiber board, and surmounted upon the member 16 are a plurality of spaced parallel members 17, which extend transversely of the members 15. The outer members 17 are 80 spaced from the extremities of the members 15 to form a support for the side walls of the compartment and secured across the members 17 is a member 18 constructed of sheet material, such as fiber board. 85

The support for the refrigerator comprises a base member embodying a frame 19, the members of which frame are connected at the corners thereof by means of a tongue and groove connection 20, 21, and are secured in any suitable manner. 90

Secured within the frame thus formed is a sheet of fiber board 22, the edges 23 of which terminate short of the base of the groove 24 so as to permit of a slight movement of the member 22 with respect to the frame, in the event of any swelling or contracting of the material. The bottom of the groove 21 adjacent the tongue 20 is of a greater depth than the remaining portion 95 of the groove, so that the tongue may extend into the adjacent member for a considerable distance. The frame thus formed is supported by means of suitable legs 25.

The bottom support for the refrigerator 105 is of any desired size and configuration according to the size and configuration of the superstructure, and placed upon this sup-

port is the bottom element of the inner compartment, shown more clearly in Fig. 6, and this bottom element is provided with apertures 26 in the members 16 and 18 which 5 register with each other and also register with an opening in the portion 22 of the supporting base and through which registering openings the drain pipe 27 passes.

The back member of the inner compartment 10 is also constructed as a section or unit and comprises a frame 28, having a central reinforcing or supporting rib 29 extending longitudinally thereof and secured to the faces of the frame are fiber board elements 30.

The frame 28 is preferably of a construction slightly heavier or of a greater width than the frames of the other sections so that 15 when the side sections or units are placed upon the bottom element as already described, the members of the frame will project beyond the side units to terminate flush with the outer edges of the members 14 of the side units as shown more clearly in 20 Fig. 4.

Corner members 31 are secured to the frame 28 to extend lengthwise thereof and an intermediate reinforcing rib 32 is also secured to the back unit and projects laterally therefrom. The outer faces of the 25 elements 31, 32 terminate substantially flush with each other and the outer edges of the members 31 also terminate flush with the outer edges of the frame 28, while the upper extremities of the elements 31—32 terminate flush with the upper extremities of the members 14.

The top unit of the inner compartment 30 comprises a frame 33 secured to the faces of which frame are fiber board members 34, so as to form a dead air space within the frame.

In assembling this portion of the refrigerator, the side walls are placed in position upon the bottom section, Fig. 6, so as to fill 45 the space between the edges of the element 18 and the extremity of the members 15, with the laterally projecting uprights 14 extending outwardly. The top section is then placed into position upon the upper edges of 50 the frames 10 and to one side of the upper edges of the upright members, which latter project beyond the frames 10. The top edge of the rear section terminates flush with the tops of the frames 10 as shown more clearly 55 in Fig. 2, and the top unit is of such a size that the outer edge of the rear of the frame will stand substantially flush with the outer fiber wall or portion 30. These parts may then be secured together in any desired or 60 suitable manner and when thus secured in position, it will be manifest that the inner casing is constituted of side, back top and bottom walls having dead air spaces 35.

The outer casing of the refrigerator is 65 formed by means of sheets of fiber board 36,

37, secured respectively to the outer edges of the upright members 14 of the side walls, and the outer faces of the members 31, 32 of the rear wall or unit, and these fiber walls are secured in position in any suitable manner. The top of the outer casing is constructed of a frame 38 which rests upon the upper edges of the uprights 14 and the top of the frame 28, as well as the uprights 31. This frame 38 is of a size to abut the fiber 70 walls 36, 37, and if desired a central or reinforcing member 39 may be provided in the frame. The frame is of such a size that it will extend beyond the rear edge of the upper unit 34 of the inner casing as shown 80 more clearly in Fig. 2, to form a communicating passage 40 between the elements 34 and a fiber board element 41 secured to the top of the frame 38, and the dead air space 42, in the rear wall, or a portion of the frame 85 38 may be cut away (see Fig. 2) as at 43 for that purpose.

With the parts thus constructed, it will be seen that the dead air spaces 42, 44 in the back, side and top walls of the outer casing 90 have communication not only with the space between the top of the inner and outer casings, but also with the dead air spaces 45 between the bottom of the inner and outer casing so that in the event that any portion 95 of the outer dead air space should cause the air therein to be heated, through any means, there will be a circulation set up in the outer dead air spaces to cause the heated portion to be equally distributed and thereby reduce 100 the temperature of the air in any one portion of the outer casing.

The front of the refrigerator is constructed in any suitable manner preferably of a suitable frame work 46 secured in position in any suitable manner and which frame work is provided with suitable door openings 47 in which are arranged suitable doors 48. Each of the doors is provided with a panel 49 constructed of fiber board and a wall 50 also constructed of fiber board and spaced from the panel 49. The space thus formed is divided by a partition 51, preferably constructed of thinner fibrous material, and a lining 52 preferably of sheet metal is 110 arranged adjacent the wall 50. The doors thus constructed and operating to close the openings 47 abut against suitable jambs 53.

The inner walls of the innermost casing 115 may be lined with any suitable material 54, such as sheet metal or the like and a partition 55 may be provided to divide the casing into an ice compartment 56 and a food compartment 57, the ice compartment being provided with suitable flues 58 and the partition 120 55 being provided with a suitable opening 59 so as to permit circulation of the air within the compartment. The drain pipe 27 being connected with the ice compartment 125 in any suitable manner to carry off the water 130

of condensation. Obviously suitable shelves, not shown, may be provided in the food compartment.

In order to protect the outer edges of the outer casing and to reinforce the structure as well as cover the joints, the edges may be bound or covered by suitable sheet material 60 preferably of metal.

With this improved construction, it will 10 be manifest that the refrigerator is so constructed that the inner compartment will be surrounded by dead air spaces and these dead air spaces will form a complete and thorough insulation for the inner compartment. The dead air spaces themselves being 15 surrounded by other dead air spaces which latter have communication with each other, a limited circulation of the air therein may be obtained, which will protect the innermost dead air spaces and as a result, a thoroughly insulated refrigerator will be produced, which will at the same time be moisture proof and will be light and durable in construction.

25 While of course many changes may be made in the details of construction, the preferred form of construction has been herein shown and described.

What is claimed as new is:

30 1. A refrigerator embodying a plurality of independent wall elements, each of said elements embodying a frame, fiber board secured to the frame to form a closed dead air space, spaced laterally projecting 35 spacing members secured to one face of the element and extending thereacross, said elements being assembled to form the sides,

backs, top and bottom of an inner casing with the said spacing members projecting from the outer faces of the walls, the front of 40 the casing being shaped to form an entrance opening, fiber board secured to the said spacing members and defining the outer walls of the refrigerator, and a closure for the said entrance opening. 45

2. A refrigerator embodying an inner chamber having an entrance opening through one side thereof, the sides, back, top and bottom thereof being constructed of independent unit sections, each of which is hollow to form closed dead air spaces about the chamber, an inclosing casing for the chamber said inclosing casing having an opening through the side thereof, a closure for the open sides of the chamber and casing, the 55 said casing being spaced from the walls of the chamber to form an air circulation passage around the chamber, laterally projecting spacing members extending from the outer faces of the upright wall units for 60 spacing the casing and chamber, and to which spacing members the outer casing walls are secured, and binding members secured over the adjacent edges of the outer casing walls. 65

In testimony whereof I have signed my name to this specification, in the presence of two subscribing witnesses, on this 25th day of October, A. D. 1917.

LOUIS F. PERKETT.
